UNITED STATES PATENT OFFICE

2,463,220

RATCHET WRENCH

William E. Van Hoose, Los Angeles, Calif.

Application September 19, 1944, Serial No. 554,768

10 Claims. (Cl. 192—45.1)

1

This invention relates to ratchet wrenches.

An object of this invention is to provide a ratchet wrench construction wherein the ratchet effect is obtained by means of a toothless construction.

Another object of this invention is to provide a reversible wrench construction which eliminates the usual pawl and ratchet elements, but at the same time provides an assembly or unit which is capable of being readily locked in either direction and which will rotate or swivel in the opposite direction.

A further object of this invention is to provide a reversible wrench unit which includes male and female wrench elements with a reversible clutch means which may be locked against rotation relative to each other in one direction and which will permit free rotation of the wrench elements in the opposite direction.

A further object of this invention is to provide a reversible wrench assembly including male and female elements rotatably coupled together, and reversible clutch means for locking the wrench elements together against rotation in one direction while permitting free rotation of one element relative to the other in the opposite direction.

A further object of this invention is to provide an improved clutch construction which will provide for selective reverse rotation of the coupled elements, and the positive locking of the elements against rotation in the opposite direction.

A further object of this invention is to provide a novel reversing mechanism for a friction clutch.

A further object of this invention is to provide a novel association between an improved friction clutch and a novel reversing mechanism.

A further object of my invention is to provide a readily reversible clutch-type mechanism which may serve as a brake or as an over-running clutch or free-wheeling device.

A further object is to provide a pivoted dog, partial rotation of which in a given direction permits the clutching engagement of a driven and a driving element in a given direction and partial rotation of which in a reverse direction permits said clutching engagement in the opposite direction while permitting said clutching engagement in an opposed direction.

With the foregoing objects in view, and others which may hereinafter more fully appear, I have invented the device illustrated in the accompanying drawings, in which:

Figure 1 is a detail end elevation of a reversible

2

wrench unit constructed according to an embodiment of this invention.

Figure 2 is a sectional view taken on the line 2—2 of Figure 1.

Figure 3 is a sectional view taken on the line 3—3 of Figure 2.

Figure 3a is a fragmentary sectional view, similar to Figure 3, with the clutching means in clutched position.

10 Figure 4 is a sectional view taken on the line 4—4 of Figure 2 with the releasing dog in a reversed position.

Figure 5 is a sectional view taken on the line 5—5 of Figure 2.

15 Figure 6 is a fragmentary sectional view taken on the line 6—6 of Figure 2.

Figure 7 is a detail side elevation of one of the wrench elements.

20 Figure 8 is a bottom plan view of the wrench element shown in Figure 7.

Figure 9 is a perspective view of one of the segmental clutch members.

Referring to the drawings the numerals 10 and 11 designate generally a pair of wrench elements which are adapted to be locked against rotation in one direction with respect to each other by the clutch means, to be hereinafter described. Wrench element 11 includes a nut member 12 which has secured to one end thereof a plate or head 13, having an annular drum forming flange 14 formed integrally therewith. Wrench element 10 includes a body 15 having a nut socket 16 extending inwardly from the outer end thereof, and the body 15, at its inner end, is formed with a narrow flange 17 rotatably engaging within the outer portion of the drum 14.

25 A ring 18 is secured to the outer end of the drum 14, by fastening members 19, which overlaps the flange 17 so as to thereby rotatably secure the wrench element 10 in the drum 14.

The drum 14 has loosely mounted therein, a pair of segmental clutch members 20 and 21 which have their inner straight faces 22 and 23 respectively in parallel spaced apart relation. Segmental members 20 and 21 are interposed between the inner end of wrench element 10 and the inner face of plate or head 13. The block 24 is somewhat loosely interposed between the straight sides of clutch members 20 and 21 adjacent one end thereof, and the block 24 is mounted in a slot 25 which is formed in a disk 26 interposed between the clutch members 20 and 21, and the inner face of plate or head 13. The block 24 together with the disk 26 acts as a positioning element serving to keep the clutch members in a

substantially constant relationship to the clutching surface and to each other thereby retaining the several parts of the unit within operative limits. Other forms of spacing members serving such function may be employed.

A spring 27, which is mounted in a socket 28, formed in the plate or head 13, bears against the adjacent face of disk 26 and constantly urges disk 26 into engagement with clutch members 20 and 21 so as to yieldably hold these clutch members against rotation with respect to disk 26, and plate or head 13. Said spring is optional and is not essential to my clutch mechanism.

Wrench member 10, at its inner end, is formed with a stud 29 projecting between members 20 and 21 and the stud 29 is formed with diametrically opposed flat faces 30 and 31 which confront somewhat loosely the flat sides 22 and 23 respectively when the clutch is not under operational tension and which bear against said clutch members, or either of them, so as to force them radially or, in any event, outwardly into a position to lock the clutch mechanism.

A releasing dog 32 is disposed in the space between the flat sides 22 and 23 adjacent the ends of clutch members 20 and 21 opposite from block 24. The dog 32 is secured to a shaft 33 rotatably engaging in an opening 34 formed in wrench member 10, shaft 33 being parallel with the longitudinal axis of wrench member 10. Wrench member 10 is formed with a laterally opening slot 35 at a point outwardly from the holding ring 18, and the dog operating lever 36, which is secured to shaft 33, extends through the slot 35.

In the use and operation of this reversible wrench unit, the operator may be connected to either one of the wrench members 10 or 11. If the article which is to be tightened or loosened is formed with a socket the operator is engaged with socket 16, and the nut member 12 is inserted in the socket of the article. If the article is to be unthreaded dog 32 is turned to the position shown in Figure 3, wherein one end of this dog will engage flat face 23 of clutch member 21, and the other end of dog 32 will be spaced from flat face 22 of clutch member 20. Wrench member 10, upon being rotated in a counter-clockwise direction, will cause cam stud 29 to partially rotate between clutch members 20 and 21, flat faces 30 and 31 of cam member 29 bearing against the confronting flat faces 22 and 23 of clutch members 20 and 21 so as to thereby force these members outwardly and into binding engagement with the inner side of drum 14.

As the member 29 is partially rotated, dog member 32 will be swung in the direction of clutch member 20, as shown more clearly in Figure 3a. In the position of cam member 29 shown in Figure 3a, the wrench member 10 is locked against rotation in a counter-clockwise direction due to the camming action of the cam member 29. With dog member 32 in the position shown in Figures 3 and 3a, if wrench member 10 is rotated in a clockwise direction, the end of dog member 32, which contacts flat face 23 of clutch member 21 in Figure 3, will engage this latter flat face at the time flat face 31 of cam member 29 is substantially parallel with segment face 23 or before the operative faces of the cam member 29 are brought to bear forcefully against the clutch members 20 or 21 or either of them. Continued rotation of wrench member 10 in a clockwise direction will cause dog member 32 to effect rotation of clutch members 20 and 21, clutch member 20 being

turned within the drum by reason of the position of block 24 between the two clutch members.

It will, therefore, be apparent that where dog 32 is in the position shown in Figures 3 and 3a, wrench member 10 may be freely rotated in a clockwise direction, but wrench member 10 will be locked against rotation with respect to wrench member 11 in a counter-clockwise direction.

In the event it is desired to have wrench member 10 freely rotate in a counter-clockwise direction, and to be locked with respect to wrench member 11, in a clockwise direction, dog 32 is swung to the position shown in Figure 4. In this latter position of dog 32 the operation will be the same as for dog 32 in Figures 3 and 3a except that the opposite end of dog 32 will contact flat face 22 of clutch member 20 and thereby prevent the rotation of the cam 29 relative to the clutch members or friction shoes 20 and 21.

Although I have herein shown and described my invention in what I have conceived to be the most practical and preferred embodiment, it is recognized that departures may be made therefore from within the scope of my invention, which is not to be limited to the details disclosed herein but is to be accorded the full scope of the claims so as to embrace any and all equivalent devices.

It is obvious, for example, that one cam face and one clutch or segmental member will suffice for the operation of my clutch, and that the faces of the clutch member and the cam may be of any desirable shape. Likewise the block 24 or disk 26 may be altogether omitted if the clutch members 20 and 21 are otherwise held at their ends, or may be of a different form, as for example, in two parts such as pins suitably retained in the disk 26, or abutting extensions of the clutch members themselves.

It will also be apparent from the description contained in the specification and claims that my clutch mechanism is suitable not merely for wrenches, but for any type of clutch application or as a brake or free-wheeling device. It is likewise apparent that the clutching action will be positive, quiet in operation, and effective with or without the use of springs or other tensioning devices.

The term clutch throughout the claims is to be understood as including not only a clutch but a brake or free-wheeling device as well.

I claim:

1. A reversible wrench comprising a pair of wrench elements rotatably coupled together, one of said elements including a drum forming cylindrical flange, a pair of segmental clutch members within said drum, a block interposed between said clutch members adjacent one end thereof, a releasing dog rotatably carried by the other of said wrench elements and disposed between said clutch members oppositely from said block, and a cam fixed relative to said other wrench element and engaging between said clutch members, said cam being positioned between said block and said dog, said dog, upon adjustment thereof to one position contacting at one end thereof with the flat inner side of one segmental member to thereby provide for holding said segmental members against rotation in one direction with respect to said cam.

2. A friction clutch comprising a driven element and a driving element, one of said elements having an axial bore, the other element having an axial extension in said bore provided with a cam face disposed toward a portion of the wall of the bore, a friction shoe disposed between and

releasably lockable by and between a wall of the bore and the cam face when said face and said wall are relatively rotated, a pivotally mounted dog selectively engageable with the shoe at a point spaced from the point of contact between said cam face and said shoe and when so engaged preventing said locking engagement of said cam.

3. A reversible wrench unit comprising a pair of axially aligned elements, a drum carried by one of said elements, means rotatably securing the other of said elements to said drum, a segmental clutch member disposed in said drum, a cam carried by the other of said aligned elements engaging said clutch member whereby rotation in either direction of said cam effects a locking of said cam and said segmental member relative to said drum, and pivotal means for causing said segmental member to rotate freely with said cam in a selected direction within said drum preventing said locking in said selected direction.

4. A reversible wrench unit comprising a pair of axially aligned elements, a drum carried by one of said elements, means rotatably securing the other of said elements to said drum, a pair of segmental clutch members disposed in said drum and having thin straight edges substantially parallel and spaced apart, a cam carried by the other of said aligned elements engaging said clutch members until rotation in either direction of said cam effects a locking of said cam and segmental members relative to said drum, and pivotal means causing said clutch members to rotate freely with said cam in a selected direction within said drum, said latter means including a block disposed between said segmental members at one side of said cam, and a dog pivotally carried by said other aligned element engaging between said segmental members on the opposite side of said cam, said dog, upon rotation of said cam in one direction, engaging one of said segmental members to effect rotation of said segmental members with said other aligned element.

5. A reversible wrench unit comprising a pair of axially aligned elements, a drum carried by one of said elements, means rotatably securing the other of said elements to said drum, a segmental clutch member disposed in said drum, a cam carried by the other of said aligned elements engaging said clutch member whereby rotation in either direction of said cam effects a locking of said cam and segmental member relative to said drum, and pivotal means causing said segmental member to rotate in a selected direction with said cam preventing said locking engagement in said selected direction, said latter means including a positioning device disposed at one side of said cam and a dog pivotally carried by said other aligned element engaging said segmental member in at least one position of said dog to effect rotation of said segmental member and said positioning device therewith.

6. A reversible wrench comprising a pair of wrench elements rotatably coupled together, a drum-forming cylindrical flange on one of said elements, at least one segmental clutch and at least one positioning device within the drum, a rotatably mounted releasing dog carried by the other of said wrench members engageable within the drum, and a cam positioned within the drum, facing said flange and engageable with said clutch member, said dog, upon rotatable ad-

justment thereof to a selected position causing said segmental member and said positioning device to rotate freely with said cam.

7. In a clutch comprising a driving element including a central cam, a driven element and a clutch member disposed between the elements and normally lockingly engageable between the cam and the driven element in either direction of relative movement of said cam and driven element, a rotatably mounted dog upon one of the elements operative in a selected position to hold the clutch member out of said locking engagement in a selected direction of rotation of said driving element.

15 8. In a clutch comprising a driving element, a driven element, a cam operatively mounted on one of the elements, a clutch member disposed between the elements and lockingly engageable between the cam and the other element upon slight relative rotating movement of said elements, a dog pivotally mounted upon an independent axis at one side of the cam-carrying element selectively engageable in at least one pivotal position to prevent said locking engagement, and means normally holding the clutch member in proximate engageable position relative to said cam and said other element.

20 9. In a clutch comprising a driving element including a central cam, a driven element and a clutch member disposed between the elements and normally lockingly engageable between the cam and the driven element in either direction of relative rotative movement of said cam and driven element, a rotatably mounted dog upon one of the elements engageable in at least one selective position to prevent the clutch member from making said locking engagement in said selective position, and manipulative means associated with said dog for selectively altering its position so as to permit the interlocking of said elements against relative movement in a desired direction and vice versa.

25 10. In a clutch comprising a driving element including a central cam, a driven element and a clutch member disposed between the elements and normally lockingly engageable between the cam and the driven element in either direction of relative movement of said cam and driven element, a rotatably mounted dog upon one of the elements and engageable in at least one rotative position with the clutch member to prevent said locking engagement of the clutch member in said position, and a finger piece accessible from without said elements associated with said dog for selectively altering its position so as to selectively permit and prevent the interlocking said elements against relative rotation in a desired direction.
